UNITED STATES PATENT OFFICE

LOUIS OSKOW, OF BROOKLYN, NEW YORK, ASSIGNOR OF ONE-HALF TO MORRIS KIRSCHSTEIN, OF NEW YORK, N. Y.

TELEVISION APPARATUS

Application filed November 8, 1928. Serial No. 317,911.

This invention relates to television.

One object of the invention is to provide a scanning means and method whereby effective scanning may be had for large areas and at great frequencies with apparatus of very compact construction having comparatively small moving parts that may be readily assembled into a neat and compact unit.

A further object of the invention is to provide a scanning means and method having simple means for varying the size of the beam of light incident upon the subject to be scanned.

A still further object of the invention is to provide in a scanning means and method wherein the scanning is accomplished by means of a light beam moving successively in a plurality of straight lines.

Another object of the invention is to provide a scanning apparatus in which synchronization between the transmitting and receiving apparatus may be positively maintained.

A further object of the invention is to provide apparatus of the character described which shall be comparatively simple and inexpensive to make, and yet highly practical and efficient in operation.

Other objects of this invention will in part be obvious and part hereinafter pointed out.

The invention accordingly consists in the features of construction, combinations of elements, and arrangement of parts which will be exemplified in the construction herein-after described, and of which the scope of application will be indicated in the following claims.

In the accompanying drawings, in which is shown one of the various possible illustrative embodiments of this invention.

Fig. 1 is a generally diagrammatic view of the apparatus and electrical system embodying the invention as applied to conductor wires transmission;

Fig. 2 is a front view of the sending apparatus with parts broken away;

Fig. 3 is a partial cross-sectional view taken on line 3—3 of Fig. 2;

Fig. 4 is a cross sectional view taken on line 4—4 of Fig. 2;

Fig. 5 is a front view of the receiving apparatus;

Fig. 6 is a cross-sectional view taken on line 6—6 of Fig. 5;

Fig. 7 is a partial cross-sectional view taken on line 7—7 of Fig. 5;

Fig. 8 is a side view of the shutter with parts broken away, and;

Fig. 9 is an exaggerated view showing the shutter slit, and the laminated member in several relative positions.

Referring in detail to the drawing, Fig. 1 diagrammatically shows the system and apparatus embodying the invention. As seen in said figure, the system comprises a sending station A and a receiving station B. The sending station A generally comprises a scanning device 10 consisting of a screen 11, illuminating means 12 and a shutter 13, and device 14 to operate said shutter 13.

Said device 14 includes an electro-magnet 15 having a coil 16 connected at one end 17, thru a make-and-break switch 18, to a wire 18a leading to the receiving station B. The opposite end 19 of said coil 16 is connected thru a variable resistance 20 to one lead 21 of a source of electric power 22. The second lead 23 of said power supply 22 is grounded as at 24.

At the sending station A, a photoelectric cell 25 is associated with the scanning device in a manner hereinafter described in detail. Said cell 25 is preferably connected to an amplifying outfit 26 thru conductor wires 27, 28, one of said wires 27 being grounded as at 29 beyond the amplifying station. The other wire 28 leads to the receiving station B.

The receiving station B is likewise provided with a scanning device 10a, substantially similar to scanning device 10 at the sending station, and comprises a screen 11a and shutter 13a. The illuminating means for the scanning device 10a comprises a neon tube 30 connected at one terminal to said conductor 28 coming from the sending station A. The other terminal of said tube is grounded as at 31.

The shutter 13a is actuated by an electro-magnetic device 14a provided with a coil 16a.

One end 17a of said coil 16a is connected to said conductor wire 18a leading from the sending station. The other end 19a of said coil is grounded as at 24a, a variable resistance 20a being interposed in said wire 19a.

5 An electric power source 32 connected to the amplification outfit 26 supplies the current to the conductors 27, 28, photoelectric cell 25, and neon tube 30, the circuit thru 10 said devices being completed by said grounds 29, 31.

Proceeding now to a detailed description 15 of the apparatus, the apparatus of the sending station A is shown in Figs. 2, 3 and 4 to be mounted on a base plate 40 having a pair of spaced L-shaped supports 41 secured thereto. Each of said supports comprises a foot portion 42 attached to said base, as by 20 studs 42a, and nuts 42b, and a vertical up- standing leg 43 extending upwardly from 25 said foot portion. Secured to said legs 43 in any suitable manner, is a lamp casing 44 comprising a bottom wall 45, somewhat spaced above base 45, a top wall 46 and a sub- 30 stantially cylindrical side wall 47 received within flanges 45a, 46a extending inwardly from said bottom and top walls respectively. Said wall 47 terminates in flat aligned portions 48, secured in any suitable manner to 35 said legs 43. The lamp casing 44 may be further supported on base 40 by studs 42a extending thru suitable openings in said bottom wall 45 and nuts 49 screwed on said studs at each side of said bottom wall. The 40 top wall 47, and the flange 46a thereof provided with bent openings 46b to permit circulation of air to the interior of the casing.

An electric bulb 50 for providing light 45 for the scanning device, may be mounted on the bottom wall 45, the base 51 of said lamp 50 extending thru said bottom wall 45 to expose the terminals thereof for connection to any suitable source of electric power (not shown). A number of similar mirrors 52 55 may be secured to the inner surface of wall 47 for reflecting the light from bulb 50 thru the space 75 between portions 48 of the casting to the screen 11 and shutter 13 of the scanning mechanism 10.

50 Said screen and shutter are supported in arms 55, 56 extending from each of legs 43. To this end said arms 55 are formed with an aligned dove-tailed groove 57. A frame member 58 may be suspended from said arms 55 by dove-tailed portion 59 engaging said groove 57. A second frame member 60 substantially symmetrical to said frame 58 may be secured to said frame 58 at one end thereof by connecting member 61 and studs 62. 60 Said studs extend thru suitable threaded openings 63 in said connecting member 61 and threaded openings 64 in lugs 65 extending from said frame members 58, 60. Lock nuts 66 may be provided for locking 65 said studs in any desired adjustable posi-

tion. The opposite ends of said frame members 58, 60 may be connected by an integral end wall 67. The inner faces 58a, 60a of said frame members 58, 60 are provided with similar grooves 58b, 60b respectively. A 70 laminated member 68 may be received between the frame members 58, 60 comprising a number of vertical flat thin, preferably rectangular strips 69 the end portions of which are received in said grooves 58b, 60b. 75 Thin plates 70 are interposed between the strips at each end to form a number of narrow slots 71 between said strips. A heavy end plate 72 may be interposed between the laminated member 68 and the studs 62 to 80 allow for tightening the strips 69 and plates 70 against the end wall 67 in assembling the parts of the screen. The strips 69 are of greater width than the slots 71 which are very narrow.

85 Means is provided for moving the entire screen 11 longitudinally to adjust the position of the screen with respect to the opening 75 of the lamp casing 47. To this end, arms 56 terminate in aligned bearing portions 76 receiving a rod 77. A worm gear 78 is fixedly mounted on said rod 77 between said bearings 76, said rod extending beyond one of the bearings 76, and terminating in a finger head 79 for rotating the rod. The under portion of frame member 58 is formed with a racked surface 80 for cooperating with the worm gear 78. Rotation of said rod obviously will move the screen 11 to the right or left depending upon the direction of rotation. The arms 56 support the worm gear 78, and thus aid in supporting the screen 11 in proper position.

90 Said frames 58, 60 are also provided with means for slidably supporting the shutter 13. Said means comprises a longitudinal extension 81 projecting from frame 58, formed with a groove 82 in the under face thereof. The lower frame 60 is provided with a longitudinal extension 83 provided with a V-shaped groove 84 receiving ball bearings 85. A plate 86 may be secured at its upper edge portion to a plate 86a having a portion 87 receivable in said groove 82. At its lower edge, said plate 86 is secured to a plate 88 having a V-shaped groove 89 in its lower face, complementary to groove 84, and also receiving said ball bearings with a vertical rectangular elongated opening 90 substantially the height of the slots 71 in screen 11.

95 A plate 91 may be secured to said plate 86, in spaced relation thereto, by a Z-shaped bracket 92 at one end and by a stud 93 at the other. Said bracket 92 is provided with a foot portion 94 secured to said plate 86 as by a small bolt 95, and with a foot portion 96 secured to plate 91, as by a stud or pin 97 and lock nuts 98. One end 100 of a connecting rod 101, the function of which will appear hereinafter, is loosely received on the stud 100

93 between a pair of nuts 102. A nut 103 screwed on said stud 93 clamps the plate 86 to an adjacent nut 102. Said plate 91 is positioned close to screen 11 and is provided with 5 an opening 104 similar to and aligned with opening 90 in plate 86.

An adjustable shutter member 105 may be pivotally mounted with respect to plate 86. Said member 105 comprises a plate 106 10 pivotally mounted on stud 97 between plate 91 and an adjacent nut 98. Said plate 106 is provided with a pair of spaced outstanding lugs 107. A plate 108 substantially symmetrical to plate 106 and provided with 15 spaced outstanding lugs 109, is adjustably secured to said plate 106 in the same plane therewith. To effect this adjustable attachment, studs 110 are secured to lugs 109 and extend thru suitable apertures in lugs 107.

20 Said studs are secured to lugs 107, 109 by a pair of lock nuts 111 to effect the adjustment in the well known manner. Said plates 106, 108 are provided with adjacent knife edges 106a, 108a respectively, substantially in 25 alignment with openings 90, 104. Adjustment of lock nuts 111 will vary the width of the slit 112 between the knife edges. The shutter may be adjusted to member 105 in various angular positions. To this end a Z- 30 shaped member 112 is rigidly secured at one arm 113 to plate 91, preferably by clamping said arm to said plate by the nut 102 adjacent said plate 91, the opposite arm 114 of said member 112 being provided with a screw 35 threaded opening 115 receiving a small screw 116, having a pointed end 117 extending into a circular groove 118 formed in plate 109. The groove 118 forms only a small arc since only a limited adjustment 40 is necessary. Said arc is formed in a radius equal to the distance between the pointed end 117 of screw 116 and the stud 97 about which shutter member 105 is pivoted. The screw 116 may be loosened to permit the pivoted 45 movement and tightened to fix the member 105 in any adjusted position to bring the slit 112 to a slightly oblique position with respect to the slits 71 in the laminate member.

The device 14 for reciprocating the shutter 50 13 in groove 82 and on ball bearings 85, includes the connecting rod 101 connected to the stud 93 which rod is pivotally connected thru a turnbuckle 120, by bolt 121 to one end 122 of a crank arm 123. Said arm 123 is connected 55 at its lower end 124 to lug 125, secured to the base 40. The electro-magnetic device 15 for actuating the cross-arm 123 includes the coil 16 housed in a box 126 mounted on said base 40. A metallic core 127 slidably fits in said 60 coil 16 in the well known manner, and its core is connected to a rod 128, which in turn is pivotally connected to stud 129 to said crank arm 123 a short distance above the lower end 124 thereof. The stud 129 may engage a 65 small slot 129a in said arm 123 to permit re-

ciprocation of rod 128 in a horizontal plane. When the coil 16 is energized the core is magnetically attracted to the left, as seen in Fig. 2, thus rotating the arm 123 about its lower end, moving shutter 13 to the left. The 70 shutter obviously will move a greater distance than does the core 127, due to the relative lengths of arm 123 and the portion thereof of below stud 129.

The make-and-break switch mechanism 18 75 is provided for automatically deenergizing and energizing the coil 16 to produce a regular periodic reciprocation of the shutter 13 over a uniform distance. Said mechanism comprises a U-shaped member 130 adjustably 80 secured to rod 128 as by a set screw 131, and provided with parallel arms 132, 133. The latter are adjusted to move in the path of a lug 134 secured to a rod 135 which is mounted in spaced bearing members 136 for sliding 85 movement parallel to rod 128. Said rod 135 is provided with stop 137 to limit the reciprocatory movement of said rod. One end portion 138 of said rod 135 is received in a recess 90 139 formed in a small plate member 140 yielding secured to said end portion 138, as by a stud 141 and spring 142. Said stud 141 is secured to said end portion 138 and extends thru an opening in member 140. The spring 142 is interposed between said plate 140 and the head 143 of said screw 141. Said plate 140 terminates in a blade 144 adapted to engage an electrical contact member 145, attached to terminal 146 by a jumper 147. Said terminal 146 connects to one end 17 of 100 the coil 16. It will now be apparent that when coil 16 is energized and core 127 moves to the left (Fig. 2) the circuit thru the coil will remain closed until arm 133 of member 130 engages the lug 134, to move rod 135. 105 This movement will break the contact 144, 145 to open the circuit and deenergize the coil.

Means is provided for moving the core to the right automatically upon such deenergization of said coil 16. Said means comprises a tension spring 150 connected at one end to a lug 151 extending from said core 127. The opposite end 152 of said spring is adjustably connected thru a screw 153 to an upstanding arm 154 supported on said base 110 40. Said spring 150 is tensioned when the core 127 is moved to the left. Upon breaking the contact at the snap switch 144, 145, the tension in said spring retracts the core 127 and consequently the rod 128 and the member 130. When arm 132 of said member 130 strikes lug 134, rod 135 will be moved to the right and plate 144 will engage contact 145 to again complete the circuit. This cycle of 115 120 125 operation is continuous.

Shock absorbing means is provided for the rod 128. For this purpose, the upstanding arm 154 is provided with a slotted portion 155 straddling said rod 128. A pair of collars 156, 157 are loosely mounted on said rod on 120 125 130

both sides of arms 154, and collar 158 is fixed to rod 128 adjacent the stud 129. A compression spring 160 is interposed between collar 157 and collar 158, and another compression spring 161 similar to spring 160 is mounted on said rod 128 between member 130 and collar 156. Movement of the rod 128 to the right and left will be eased by springs 160, 161 when portion 155 of arm 154 strikes 10 said collars 156, 157.

As above described, one end of coil 16 connects to said binding post 146. The opposite end 19 of said coil 16 is connected to a binding post 170, and a lead 171 connects said 15 binding post 170 to one end of rheostat 20 which is mounted on the front face 172 of the box 126. The rotating contact arm 173 for said rheostat is connected thru lead 21 to one contact 174 of a switch 176 connected 20 to the power source 22. The other contact 175 of said switch is connected to said power source 22 which is provided with a lead 23 grounded at 24 as shown in the wiring diagram in Fig. 1.

25 The circuit thru the coil 16 connects to the receiving station B thru lead 18a. The connection for said lead 18a at the sending station comprises a spring arm 180 having sliding contact with rod 135. Said arm 180 may 30 be secured to base 40 as at 181. It will be understood that as the circuit thru the coil 16, completed and broken, so will the entire circuit, including the conductor 18a be completed and broken.

35 The receiving apparatus shown in detail in Figs. 5, 6 and 7 is mounted on a base 40a. Said apparatus is similar in most respects to the sending apparatus described above, and comprises a lamp casing 47a, a screen 11a, 40 and the shutter 13a all similar to casing 47, screen 11 and shutter 13. A detailed description of these parts of the receiving station and also of the electro-magnetic actuating device 14a is therefore not necessary in 45 view of the full description of the sending station, and only the differences in the structure will be described.

The receiving station B is not provided with any make and break mechanism for the 50 coil 16a, since the circuit thru said coil is controlled at the sending station. One end 17a, of coil 16a is connected to the binding post 186 to which the conductor 18a coming from the sending station is connected. The 55 coil 16a is in the same circuit as coil 16 and thus the core 127a is actuated in synchronism (for a purpose hereinafter appearing) with core 127. A retracting spring 150a is provided for said core 127a. The opposite end 19a of coil 16a is connected to terminal 187 of the rheostat 20a. The rotating contact arm 173a for said rheostat is connected by a lead 21a to one contact 174a of a switch 60 176a. The other contact 175a of said switch

is grounded in any suitable manner as shown at 24a in Fig. 1.

It will be noted that the illuminant for the casing 47a is a neon tube 30. One terminal 188 of said tube is grounded in any suitable manner as shown at 31 in Fig. 1. The other terminal 189 for said neon tube extends to an ordinary amplification outfit 26. This outfit may comprise the usual amplification set and therefore no detail showing of the same is included. The amplification outfit may be connected by wires 27, 28 to a photoelectric cell 25 which may be mounted on the cover 46 of casing 47. The cell 25 is preferably mounted for universal adjustment. To this end the base 190 of said cell is mounted on a U-shaped bracket 191 having arms 192 pivotally mounted on a pin 193, extending thru arms 194 of a U-shaped member 195. A wing nut 196 screwed on pin 193 tightens the cell 25 in any desired adjusted position in a plane transverse to said pin 193. Said bracket 195 is provided with a depending threaded portion 197 extending thru an opening 198 in said cover 46. Said portion 197 receives a nut 198a. A spring washer 199 may be interposed between said nut 198a and the under surface of said cover 46. This construction permits rotation of said brackets 195, 191 and cell 25 about a vertical axis. The cell 25 may thus be swivelled into any desired angle.

The sending station A is also provided with a small mirror 200 mounted on member 200a secured to frame 55 centrally with respect to the opening 75 in the lamp.

Another difference between the receiving and sending stations is that the receiving station B is provided with a lens 201 mounted in an annular socket 202 formed integrally with frames 58B, 60B mounting the screen 11a.

The receiving station B is further provided with screen means for the images transmitted thereto from the sending station A. For this purpose, a pair of spaced parallel walls 205 extend upwardly from arm 55c integrally formed with supporting legs 43a. Said walls 205 are provided with aligned apertures 206 centrally located with respect to said screen 11a. The smooth end 207 of a screw threaded shaft 208 is received in said openings 206. Collars 209 may be secured to said shaft 207 as by set screws 210 adjacent said walls 205 to prevent longitudinal movement of shaft 208 in either direction.

Said walls 205 are further provided with a pair of aligned openings at each end thereof for similarly mounting the end portions of guide rods 216 in spaced parallel relation to shaft 208 on each side thereof. A screen member 214 is mounted on said shaft 208 and rods 216 for longitudinal adjustment with respect to the scanning

device 10a. Said member 214 comprises a frame 213 provided with an upstanding internally screw threaded boss 212 adapted to coact with the threads of shaft 208. Said frame is further provided with a pair of upstanding ears 217 apertured as at 218 for slidably receiving said rods 216. The screen 214 is preferably attached to said frame 213 by a supporting member 219 extending around the perimeter of said frame and provided with an inturned edge 220 for engaging said screen. The outer free end of said shaft 208 terminates in a head 211 for rotating said shaft. Manipulation of said head 211 to rotate said shaft will move said screen 214 toward or away from the scanning device to any desired adjusted position.

The operation of the system is as follows:—

20. Starting at the sending station A with the switch 176 closed (similar switch 176a at the receiving station also being closed) and the bulb 50 of the illuminating device 12, lit, the object or person X whose image is to be transmitted is placed in front of the shutter 13. This object or person can be properly positioned by observing the mirror 200. This mirror is preferably so tilted that a person seeing his image centrally in the 25 mirror, is properly stationed with respect to the scanning device. The proper position is centrally of the opening 75 in the lamp 12.

The shutters 13 at the sending station and the shutter 13a at the receiving station will 30 reciprocate in synchronism. Thus when coil 35

16 is energized and attracts its core to move the crank arm 123 and shutter 13 in one direction, coil 16a is also energized, (said coils being connected in series) and attracts its core to move crank arm 123a and shutter 13a in the same direction. When the circuit is broken at the end of the stroke, both coils are deenergized and springs 150, 150a 40 retract cores 127, 127a respectively to move shutters 13, 13a in the opposite direction. The springs 150, 150a may be adjusted and so may the rheostats 20, 20a to ensure a proper synchronization of the two shutters.

45 As the shutter 13 of scanning device 10 reciprocates, the only light that can pass from the lamp 12 to the object X is light that passes thru the lamp casing, the screen 11 and the shutter 13. The light passes thru opening 75 in the lamp. Light may pass thru the narrow slits 71 in the screen 11. But 50 only the light that can penetrate the slit 112 which is disposed in alignment with openings 90, 104 in plates 86, and 91 respectively will reach the object X.

55 The shutter member 105, however may be angularly adjusted, and is so adjusted to dispose the slit 112 therein at a small oblique angle with respect to slits 71 in the screen. Thus the slit 112 cuts slits 71 at an 60 angle and light may pass the shutter only

where these slits are superimposed. The slits 71 and 112 may be made so narrow and the angle of the latter so adjusted that a very small area Y, probably no bigger than a pinhead, can be penetrated by light from the lamp 12 at any one time. The thickness of the laminated strips 69 is preferably such that each strip may entirely cover the oblique slit 112. Thus the slit 112 can at no time overlap any parts of two adjacent slits 71.

70 When the shutter 13 is moved, the slit 112 moves across the face of the laminated member 68. Supposing the shutter 13 to move to the left, looking at Fig. 2, and the slit 112 so adjusted that its bottom portion is further to the left than the top portion, it will be apparent that the slit 112 will cross a slit 71 at its bottom portion first and that this overlapping portion will gradually move up said slit 71 as shown at Y and Y1 respectively in Fig. 9. The last point of overlapping will thus be when the top portion of slit 112 crosses the top portion of slit 71 as seen at Y2 in Fig. 9. Thus the penetrating portion or the illuminated spot has travelled 75 in a vertical line from bottom to top.

80 As soon as the bottom portion of said slit 112 overlaps the bottom portions of the next slit 71 the illuminated spot travels up an adjacent line. And thus the movement of the shutter causes a single beam or pencil of light 85 to traverse the object X in a number of straight lines in rapid succession from the right to the left.

90 Upon return movement of the shutter 100 (from left to right) the top portion of the slit 112 first overlaps the top of the slit 71, and the overlapping portion travels down the slit 71. In this manner, a travelling beam 95 of light travelling down adjacent vertical lines in rapid succession is produced, and this beam also traverses the object X. The speed of movement of the shutter is so regulated that the object X seems to be entirely illuminated, altho at any one instant of time there 105 is really only one spot on the whole object 110 which receives light from the lamp 12.

115 The room where the object X is located is preferably darkened somewhat so as to show up the illuminated object. A background may be provided for the object X to complete the picture to be transmitted. The photoelectric cell 25 which is positioned on casing wall 46, as is well known, is provided with a light sensitive portion. This portion 120 will be sensitive to each spot of the object X which is illuminated at any one instant. The current in a photoelectric cell, as is also well known, varies in accordance with the intensity of light reflected on the light sensitive 125 portion. Thus the current in the cell 25 varies as the shutter moves in accordance with the brightness of the spot on the body X which is illuminated at any one time.

130 When a dark portion of X is illuminated

the current will not be as great as when a lighter spot is illuminated. The variation in current may be amplified by the usual amplification means 26. The current also passes to the neon tube 30 which is in series circuit with the amplifier 26, and therefore takes the same relative current as the photoelectric cell. Thus the current passing thru the neon tube varies in accordance with the variations in the cell 25. As is well known, the brightness of a neon depends upon and varies with the current passing therethru. This tube is sensitive to very rapid changes and thus light in casing 47 therefore varies rapidly in accordance to the brightness of the illuminated portions of object X.

Since the shutters 13 and 13a are in synchronism, a proper adjustment of the slit 112a in said shutter 13a, and proper adjustments of the screens 11, 11a by turning adjustment rods 77, 77a respectively, will cause a beam of light to pass thru the shutter 13a in a position with respect to screen 11a corresponding to the position of the spot illuminating object X at the same instant of time. This beam is thrown in screen 213 which may be adjusted for proper focal distance determined by the lens 201 thru which the beam must pass.

The beam passing thru shutter 13a also traverses the screen 213 in a number of vertical adjacent lines in rapid succession, in synchronism with the beam traversing the object X. The intensity of this beam at any instant depends upon the brightness of the neon tube 30. The brightness of any one spot of the screen 213 illuminated by the beam at any instant is therefore of equal intensity as on equivalent spot on object X, which is at that instant also being illuminated. Since the illuminated spots on the screen travels very fast, the illusion is that the entire screen is illuminated at once, and since the different portions of the screen are bright or dark in accordance with equivalent portions of the object X, a complete picture of the object is presented on the screen.

It will be understood that by properly adjusting the speed of the reciprocating shutters, pictures of moving objects may likewise be transmitted.

It will be further noted that the images may in similar manner be transmitted by radio broadcasting and reception.

It will be noted that the area of the screen traversed by the shutter may be increased either by increasing the heights of the screen and shutter or by increasing the width of the screen and the stroke of the shutter. The area of the subject scanned for a given position of the subject relative to the screen may thus be increased with comparatively small increase in the size of the apparatus and practically no sacrifice in compactness thereof.

It will be noted further that by controlling the rate of reciprocation of the shutter, great frequency of scanning may be obtained in a compact apparatus having comparatively small moving parts. This is of course of particular importance for transmission of rapidly moving objects, which in accordance with this invention may be accomplished by small and compact apparatus. A feature of this invention is thus seen to reside in the obtaining of effective scanning over large areas at comparatively high frequencies and effective light intensities, with a comparatively small size of shutter and screen. The invention thus makes possible television apparatus which is highly practical since it lends itself to embodiment in small, compact and wieldy apparatus to permit easy handling and installation in the home.

While in the embodiment herein described the screen and shutter are flat members lying in parallel planes, they may be made curved such as cylindrical, the shutter member being given an oscillatory motion on a curve parallel to the curve of the screen.

It will thus be seen that there is provided a device in which the several objects of this invention are achieved, and which is well adapted to meet the conditions of practical use.

As various possible embodiments might be made of the above invention, and as various changes might be made in the embodiment set forth, it is to be understood that all matter herein set forth or shown in the accompanying drawings is to be interpreted as illustrative and not in a limiting sense.

Having thus described my invention I claim as new and desire to secure by Letters Patent:

1. In television apparatus, a scanning device comprising a stationary screen having a plurality of openings and a reciprocating shutter having an opening adapted to overlap said screen openings, during movement of said shutter.

2. In television apparatus, a scanning device comprising a screen having a plurality of spaced, elongated openings and a reciprocating shutter having a narrow elongated opening adapted to overlap said screen openings during movement of said shutter.

3. In television apparatus, a scanning device comprising a screen having a plurality of spaced, elongated openings and a reciprocating shutter having a narrow elongated opening adapted to overlap said screen openings during movement of said shutter, said shutter opening being obliquely disposed relative to said screen openings.

4. In television apparatus, a scanning device comprising a screen having a plurality of spaced, elongated openings and a reciprocating shutter having a narrow, elongated opening adapted to overlap said screen openings during movement of said shutter, said

shutter opening being obliquely disposed relative to said screen openings, and means for varying the angle of said shutter opening.

5. In television apparatus, a scanning device comprising a screen having a plurality of spaced, elongated openings, a reciprocating shutter having a narrow, elongated opening adapted to overlap said screen openings during movement of said shutter, said shutter openings being obliquely disposed relative to said screen openings, and means for varying the width of said openings.

6. In television apparatus, a scanning device comprising a screen having a plurality of spaced elongated openings, a reciprocating shutter having a narrow elongated opening adapted to overlap said screen openings during movement of said shutter, said shutter opening being obliquely disposed relative to said screen openings, means for varying the angle of said shutter opening, and means for varying the width of said shutter opening.

7. In a system for transmitting pictures, a scanning device comprising a laminated member and a shutter movable with respect to said member, said member comprising a series of parallel plates separated by parallel openings, said shutter being formed with a narrow slit disposed at an angle to said openings.

8. In a system for transmitting pictures, a scanning device comprising a laminated member and a shutter movable with respect to said member, said member comprising a series of parallel plates separated by parallel narrow openings, said shutter being formed with a narrow slit disposed at an angle to said openings, and means for adjusting the position of said laminated member.

9. In a system for transmitting pictures, a scanning device comprising a laminated member and a shutter movable with respect to said member, said member comprising a series of parallel plates separated by parallel, narrow openings, said shutter being formed with a narrow slit disposed at an angle to said openings, means for adjusting the position of said member and means for adjusting the angular position of said slit.

10. In a system for transmitting pictures, a scanning device comprising a laminated member and a shutter movable with respect to said member, said member comprising a series of parallel plates separated by parallel narrow openings, said shutter being formed with a narrow slit disposed at an angle to said openings, means for adjusting the position of said member, means for adjusting the angular position of said slit and means for adjusting the width of said slit.

11. In television apparatus of the character described, a scanning device therefor comprising a member formed with a plurality of spaced, parallel, narrow, elongated

openings and means for exposing said openings successively, a portion only of each opening being exposed at any one instant, said exposed portion moving along the length of one of said openings and then along the length of the next adjacent opening.

12. In television apparatus of the character described, a scanning device therefor comprising a member formed with a plurality of spaced, parallel, narrow, elongated openings, and means for exposing said openings successively, a portion only of each opening being exposed at any one time, said exposed portion moving along the entire length of one of said openings and then along the length of the next adjacent opening, said exposed portions moving in the same direction in each opening in the same direction.

13. In a system for transmitting pictures, a sending station and a receiving station, a scanning device at each station and a means for actuating said devices in synchronism, said means comprising electromagnetic coils at each station electromagnets associated with said coils, and a make and break switch controlling said coils and operated by the electromagnet at one of said stations only.

14. A scanning device comprising a member provided with a series of spaced parallel slits and a member movable with respect to said first mentioned member, and provided with a slit disposed at an angle to said slits.

15. A scanning device comprising a member provided with a series of spaced parallel slits, a member movable with respect to said first mentioned member, and provided with a slit disposed at an angle to said slits and means for varying the angle of said slit.

In testimony whereof I affix my signature.

LOUIS OSKOW.
